ARTICLE OF MANUFACTURE AND PROCESS
FOR MAKING SAME

Frank A. Yokell, Gresham, Oreg.

Application February 10, 1942, Serial No. 430,184

4 Claims. (Cl. 41—35)

This invention relates generally to the wood-working art and particularly to the plywood industry and a special reference to forming of plywood and the method of producing same.

Before entering into an explanation of this invention, it must be understood that plywood is constructed of a plurality of sheets of veneer glued in a superimposed relationship to form a board in which the grain in the various layers is normal to the grain in the next adjacent layers.

It is a well known fact that with the increasing scarcity of suitable veneer logs, increasingly greater percent of the logs are used up in the making of plywood, which means that in order to obtain a good face on each ply board that a clear veneer must be used or it must be slit to remove the knots or defects, or the defects may be cut out and patched as is commonly the case so that when the board is finally finished, it will present a complete and new appearance.

Owing to the cost of labor and materials, the patching of plywood has been practically abandoned on at least one side of the board, and when knots occur on one face of the board, they must either be patched or allowed to remain vacant in case the knot should fall out. This limits the use of the board to one side and the board is sold at a reduced rate and known as a "reject."

Recently, there has been a marked increase in the adoption of knotty lumber for home finishing purposes and although plywood is commonly used for interior finish, it is difficult to maintain the knots therein owing to the fact that the veneer is thin and is caused to bend considerably before it is fabricated into plywood boards.

It is therefore the main object of my invention to construct a plywood board which will utilize the knotty portion of a veneer log and yet produce a finished lumber without danger of having the knots fall out after the fabrication thereof.

I accomplish these and other objects in the manner set forth in the following specification, as illustrated in the accompanying drawing, in which:

Fig. 1 is an enlarged, fragmentary view through a piece of plywood from which a knot has fallen out.

Fig. 2 is a plan of Fig. 1.

Fig. 3 is a view similar to Fig. 1 showing the knot hole filled with a suitable plastic.

Fig. 4 is a plan of Fig. 3.

Fig. 5 is a side elevation of a piece of transfer paper.

Fig. 6 is a plan of Fig. 5.
Fig. 7 is a section through the plywood after the imitation knot and its surrounding surface have been sanded.

Fig. 8 is a plan of Fig. 7.
Fig. 9 is a fragmentary view showing a mallet having a rubber stamp mounted on each of its heads.

Fig. 10 is a plan of the mallet head showing the rubber stamp making the annular rings.

Similar numbers refer to similar parts throughout the several views.

Referring in detail to the drawing, there is shown a piece of plywood 11 which in this case consists of three plies of veneer 12, 13 and 14.

In Figs. 1 and 2 is shown a vacant space 15 formerly occupied by a knot which had fallen out either during the cutting of the veneer from the log, or in the handling thereof.

In Figs. 3 and 4, which are similar to Figs. 1 and 2, is shown a plug 16 of plastic material such as sawdust, preferably of a dark or stained wood, or of pulverized knots themselves; the binder employed being preferably of a resinous nature which will become effective in the presence of heat.

It will be noticed in Fig. 3, that the surface 17 of the plug 16 is left somewhat rounded.

In Figs. 5 and 6 is shown a paper transfer 18 upon which are printed with transfer ink the lines 19 which represent the annular rings of the limb which form the knot. The ink, or stain, employed to make the lines 19 may be of the ordinary transfer variety or of one which will readily penetrate the plastic material 16 when heat is applied thereto.

It is important to note that before filling the space 15 with the plastic 16, it is necessary to coat the interior of the space 15 with an adhesive 20 to insure the imitation knot remaining in position.

In the formation of the imitation knot by the means thus far set forth, it is desirable to have on hand various sizes and types of transfer papers 18 in order to avoid any objectionable similarity in the knots. It will be noted that if the rings 19 on the transfer 18 are larger than the opening 15, that there will be no transferring action upon the wood since there will be a lack of moisture, but where the moist plastic occurs, the coloring matter will extend well into the material and will not be removed by the subsequent sanding thereof, although such sanding would remove any such stain as might be produced by the over-hanging rings 19.

A further advantage arising from the use of the transfers 18 exists in the prevention of a gluing action taking place between the boards themselves wherever an imitation knot is located.

In some instances, it will be found desirable to employ a mallet 21 upon whose striking faces 22 are mounted the rubber stamps 23 which are formed to resemble the annular rings of a knot. The stamp is preferably pressed against an ink pad, and then the mallet 21 is used to strike over the plastic plug 16 causing any surplus plastic to be squeezed out laterally while the stamp itself presses slightly into the space 15 forming slight annular rings which will not be obscured by the sanding process.

I am aware that it has long been the practice to fill defects in wood by means of what is known as plastic wood. It is therefore not my intention to cover such actions broadly, but I do intend to cover all such forms and modifications of the article and the method for making same, as fall fairly within the appended claims.

I claim:

1. An article of manufacture consisting of a plywood board from a flat side of which knots have been removed and the knot holes filled with soft plastic, and a plurality of annular rings formed in the body of said plastic whereby the plastic material may be sanded flush with the surface of the board without removing said rings. 30

2. An article of manufacture consisting of a plurality of plies of veneer united by adhesive to form a single board, an outermost face of which has knot holes formed therein caused by the removal of the knots during fabrication, a layer of adhesive extending across the bottom of the knot hole and around the sides thereof, a plug for said knot hole of plastic wood extending outwardly from the board, said plug having concentric rings formed therein simulating the annular rings of a limb, and extending within that portion of the plug which is within the knot hole itself.

3. A method of treating plywood consisting of coating the knot holes therein with adhesive, then filling the holes with a plastic material which is darker than the surrounding wood, then forming substantially concentric rings in said plastic in imitation of a knot, and then sanding the surface of the plywood and plastic without removing the rings therefrom.

4. A method of forming imitation knots in wood, consisting of progressively coating the sides of a knot hole with adhesive, then filling the knot hole with a plastic wood resembling in color a natural knot, then forming in the plastic material concentric rings, the marks of which extend beneath the surface of the board, and then sanding the board and knot to a common face.

FRANK A. YOKELL.
